UNITED STATES PATENT OFFICE.

WILLIAM H. PHILLIPS, OF BRIDGETON, NEW JERSEY.

DESIGN FOR A DOOR-SECURER.

SPECIFICATION forming part of Design No. 32,030, dated December 26, 1899.

Application filed November 29, 1899. Serial No. 738,740. Term of patent 14 years.

To all whom it may concern:

Be it known that I, WILLIAM H. PHILLIPS, a citizen of the United States, residing at Bridgeton, in the county of Cumberland and State 5 of New Jersey, have invented and produced a new and original Design for a Door-Securer, of which the following is a specification.

This invention relates to a new and original design for a door-securer, and the essential feature of the same resides in the general contour and configuration of the portion thereof which is to be arranged contiguous to the door.

In the drawings, Figure 1 is a top plan view 15 of a door-securer embodying the features of the design. Fig. 2 is a transverse section through the same on the line 2 2 of Fig. 1.

Similar numerals of reference are employed to indicate corresponding parts in the views. 20 The body 1 is of convex contour and has a flat base face 2. The said body has a curved

opening 3 extending through the same in a vertical direction, and continuous with the said curved opening is a straight opening 4, the opposite terminals 5 of the body forming 25 the walls for the said opening 4 being parallel. The opening 4 is of less transverse extent than the diameter of the opening 3, and the surrounding portions of the body are regularly shaped relative to the said opening. 30

Having thus described the invention, what is claimed as new is—

The design for a door-securer, herein shown and described.

In testimony that I claim the foregoing as 35 my own I have hereto affixed my signature in the presence of two witnesses.

WILLIAM H. PHILLIPS.
